UNITED STATES PATENT OFFICE.

FRANK H. CARSON, OF LOANA, WISCONSIN.

ROTARY ENGINE.

1,171,76

Specification of Letters Patent. Patented Feb. 15, 1916.

Application filed October 27, 1913. Serial No. 797,503.

To all whom it may concern:

Be it known that I, FRANK H. CARSON, a citizen of the United States, residing at Loana, in the county of Hennepin and State of Wisconsin, have invented certain new and useful Improvements in Rotary Engines, of which the following is a specification.

This invention relates to steam engines and more particularly to a rotary steam engine such as is commonly known as turbines, and the primary object of the invention is the provision of a rotary engine which is constructed so as to economically utilize steam and avoid dead-points in the rotation of the rotors.

Another object of this invention is the provision of a novel form of governing mechanism which regulates the inlet of steam into the steam chamber in accordance with the speed with which the rotors travel.

A still further object of this invention is the provision of abutment plates which automatically enter into and recede from the interior of the steam chamber during the rotation of the rotor, so as to prevent back action of the steam within the chamber.

With the foregoing and other objects in view, this invention consists in such novel features of construction, combination and arrangement of parts as will be hereinafter more fully described, illustrated in the accompanying drawings and claimed.

In describing this invention in detail, reference will be had to the accompanying drawings wherein like characters of reference designate like or corresponding parts throughout the several views, and in which,

Figure 1 is an end elevation of the improved engine; Fig. 2 is a side elevation of the improved engine showing the governing mechanism in different positions to that shown in Fig. 1; Fig. 3 is a side elevation of the engine showing the side opposite to that shown in Fig. 2; Fig. 4 is a central sectional view on the line 4-4 of Fig. 1; Fig. 5 is a cross sectional view on the line 5-5 of Fig. 2; Fig. 6 is a cross sectional view on the line 6-6 of Fig. 2; Fig. 7 is a detailed perspective view of the valve controlling the inlet of steam, and Fig. 8 is a detailed cross sectional view.

Referring more particularly to the drawings 1 designates the bed plate of the engine which has a plurality of upstanding brackets 2 formed thereupon. The brackets 2 have bearings or boxings 3 formed upon

their upper ends in which is rotatably mounted the drive shaft 4 of the engine.

The drive shaft 4 of the engine extends laterally across the bed plate 1 and has a rotor 5 rigidly mounted thereupon. The rim 6 of the rotor 5 moves in the opening 7 which is formed in the inner side of the steam casing or chest 8. The steam casing or chest 8 is circular in plan and substantially circular in cross section being composed of two sections 9 and 10 which have annular flanges 11 and 12 formed upon their inner surface. The two sections 9 and 10 are securely connected together, by means of bolts 13 which are inserted through openings in the annular flanges 11 and 12. The section 9 of the steam casing of the engine is supported by a web 14 which is formed integral with the bed plate 1 and with the section 9.

The rotor 5 has piston heads 15 and 16 securely attached thereto in any suitable manner and disposed directly opposite each other as is clearly shown in Fig. 4 of the drawings. Securely attached to one side of each of the piston heads 15 and 16 are follow plates 17. Both of the piston heads 15 and 16 are provided with cut out portions 18 formed in their outer ends, which engage the inner surface of the outer side of the steam chest 8 and the cut out portions 18 have metallic plates 19 mounted therein which metallic plates serve to absorb the wear occasioned by the continuous rotation of the rotor 5 and the piston heads 15 and 16.

The casing 8 has projections 20 and 21 formed thereupon and directly opposite to each other which projections are provided with circular shaped openings 22 extending laterally therethrough and with other circular shaped openings 23 extending longitudinally therein and communicating with the laterally extending openings 22. Valve members 24 are rotatably mounted upon pins 25 which extend laterally through projections 21 and 22. The valve members 24 have a portion of their surfaces cut away, as is clearly shown in Figs. 4 and 7 of the drawings. The portion of the valve members 24 which is cut away, forms a means of communication between the openings 23 and the openings 26 which pass through the projections 21 and 22 communicating with the openings 22 and with the interior of the casing 8. The valve members 24 fit firmly

and snugly within the openings 22 and when the portions thereof which are cut away, are not in communication with the openings 26, a fluid tight valve or stoppage for the air 5 through the openings 22 is formed.

The projections 20 and 21 have pipes 27 and 28 connected thereto, the openings in which communicate with the openings 23. The pipes 27 and 28 are connected to a single 10 pipe 29 which is in turn connected to any suitable steam supply source, providing the necessary steam or power for the propulsion of the rotor.

The casing 8 has a plurality of auxiliary casings 30 and 31 formed thereupon, which extend laterally of the casing and have blades or abutment plates 32 and 33 slidably seated therein. The abutment plates 32 and 33 have rods 34 detachably connected to 15 one end thereof which rods extend outwardly through bearings 35 formed upon the ends of the auxiliary casings 30 and 31 and are slidably seated in bearings 36 which are formed upon the outer ends of arms 37. The arms 37 are secured in any suitable manner to the auxiliary casings 31 and 30. The rods 34 extend outwardly through the bearings 36 and have coil springs 38 mounted thereabout which coil springs abut pins 39 which are inserted through the ends of the rods 34. The rods 34 have pivotally connected thereto as at 38 arms 39 which are in turn pivotally connected at 40 to the arms 41. The arms 41 are pivotally connected, by 25 means of pins 42 to brackets 43 which are carried by the casing 8. The pins 42 are rotatably journaled in a pair of brackets 43, as is clearly shown in Fig. 2, and have coil springs 44 mounted thereabout and between 30 one of the brackets 43 and the end of the arm 41 which is mounted upon the pins 42. The outer ends of the pins 42 have arms 45 rigidly mounted thereupon or formed integral therewith as is desired. The extreme 45 outer ends of the arms 45 are bifurcated and rollers 46 are mounted within the bifurcations of the arms. The rollers 46, engage, at predetermined times, cams or lugs 47 which are mounted upon one side of the rim 50 of the rotor 5. The cams or lugs 47 have their surfaces extending outwardly at an incline so that when the rollers 46 engage their surfaces and pass thereupon the arms 45 and the rods 34 will be moved or partially 55 rotated within the brackets 43. This partial rotation of the pins 42 will in turn operate the arms 41 and 39 moving the rods 34 outwardly, as is shown in the lower position in Fig. 1 of the drawings, causing the abutment plates 32 or 33 to move or recede into the auxiliary casings 30 or 31, thus providing a clear path for the piston heads 15 or 16. Immediately after the piston heads 15 or 16 have passed the abutment plates 32 or 60 33 the rollers 46 will have passed over the

lugs 47 and the springs 44 and 38, will force the abutment plates 32 or 33 inwardly into the casing, as is shown in Fig. 5, thereby preventing back pressure of the steam within the casing.

The pins 25 have rigidly mounted upon one end thereof, which end protrudes out of the projections 20 and 21, arms 50. The arms 50 extend inwardly toward the drive shaft 4 of the engine and have rollers 51 rotatably carried by their outer ends. The arms 50 have also secured thereto as at 52 one end of flat springs 53, which are secured to the casing 8 as at 54. The springs 53, tend to hold the arms 50 in a position so that the cut out portions of the valve members 24, will communicate with the openings 23 and 26 allowing the passage of steam therethrough and into the interior of the casing 8.

The rollers 51 are engaged by the outer surface of cams 55. The cams 55 have arms 56 pivotally connected thereto as at 57. The arms 56 are provided with slots 58 formed therein near the point 57, which slots have pins 59 slidably seated therein. The pins 59 are securely attached to the arms or spokes 60 of the rotor 5. The arms 56 are again pivotally connected at 61 to the short arms 62 which are formed upon arms 63. The arms 63 are pivotally connected at 64 to the spokes 60 of the rotor 5 and have weights 66 adjustably mounted upon one end thereof. The arms 63 have arms or links 67 pivotally connected to their ends opposite to the ones upon which the weights 66 are mounted which links are in turn pivotally connected to the cams 55. These various arms and the cams, together with the rollers 51 and the arms 50 form a governing mechanism for the speed of the engine in that when the speed with which the rotor 5 rotates increases, the rotation will cause the arms 56 to move outwardly upon the pins 59 and thus straighten out or force the arms 67 outwardly also. The moving outwardly of the arms 56 and 67 will in turn force the cams 55 outwardly. The forcing outwardly of the cams 55 will in turn force the arms 50 downwardly against the tension of the springs 53 and will partially rotate the valve members 24 closing, to a small extent, the communicating opening between the openings 23 and 26 thus regulating the amount of steam which enters the steam chamber.

The casing 8 is provided with openings 70 formed therein, adjacent the abutment plates 32 which openings communicate with pipes 71, and form exhaust ports for the engine. Rods 72 and springs 73 form a device the purpose of which is to catch or hold the abutment plate against the rotor 5 to prohibit the escape of steam between them. The springs 73 presses the pin or shaft against the shoe which holds the abutment

firmly against 5 when the valve is across the path of the piston.

The various mechanisms heretofore described for operating the abutment plates 32 and 33 are arranged so that the abutment plates will alternately recede from and move into the casing 8, during the different positions of the piston heads 5 and 16 as is necessary for the operating of the engine. This engine will run with one piston 15, one cut-off valve 24, and one abutment plate 32. The reason for two sets of valves and two pistons is to reduce friction on the line shaft. Retaining valve or abutment plate 33 will be open all the time except when 32 is withdrawn to permit the piston to pass at that instant. In engines of this type the economy of steam depends greatly on the expansion and therefore in this engine the steam will be shut off before the valve 33 closes. There is a small amount of power required to operate the valve 33 but this is compensated for by the use of the steam it economizes by closing off the exhaust of the steam behind the piston when the valve 33 must withdraw for the piston to pass in its path as the steam would escape behind it when 32 must withdraw except for the use of 33 closing behind it.

From the foregoing description taken in connection with the accompanying drawings the advantages of construction and of the method of operation of the improved rotary engine will be readily apparent to those skilled in the art to which this invention appertains and, while in the foregoing description, the principle of the operation of this invention has been described together with various features of construction, it is to be understood that certain minor features of construction, combination and arrangement of parts may be altered to suit practical conditions provided such alterations are comprehended within the scope of what is claimed.

What is claimed is:

1. In a rotary engine, the combination, of a casing, a rotor, auxiliary casings formed upon said casing, abutting plates slidably mounted in said auxiliary casings and adapted to be moved into or out of said casing, rods connected to said abutting plates, a plurality of levers connected to said rods, brackets formed upon said casing, pins carried by said brackets, arms connected to said pins, said arms having their free ends bifurcated, rollers seated in said bifurcations and cams carried by said rotor, said cams adapted to engage said rotors and operate said arms for moving said abutment plates out of said casing and into said auxiliary casings.
2. In a rotary engine, the combination, of a casing, a rotor, auxiliary casings formed upon said casing, abutting plates slidably

mounted in said auxiliary casings and adapted to be moved into or out of said casing, rods connected to said abutting plates, a plurality of levers connected to said rods, brackets formed upon said casing, pins carried by said brackets, arms connected to said pins, said arms having their free ends bifurcated, rollers seated in said bifurcations and cams carried by said rotor, said cams adapted to engage said rotors and operate said arms for moving said abutment plates out of said casing and into said auxiliary casings and means for automatically moving said abutment plates into said casing after said rollers have passed over said cams.

3. In a rotary engine, the combination of a casing, inlet valves carried by said casing, a rotor, auxiliary casings formed upon said casing, abutting plates slidably mounted in said auxiliary casings and adapted to move into or out of said casing, rods connected to said abutting plates, a plurality of levers connected to said rods, brackets formed upon said casing, pins carried by said brackets, arms connected to said pins, said arms having their free ends bifurcated, rollers seated in said bifurcations and cams carried by said rotor, said cams adapted to engage said rotors and operate said arms for moving said abutment plates out of said casing and into said auxiliary casings, means for automatically moving said abutment plates into said casing after said rollers have passed over said cams, and means controlled by the rotation of said rotor for regulating the passage of steam through said inlet.

4. In a rotary engine, a casing, a rotor, said rotor having a rim and spokes, piston heads connected to the rim of said rotor, inlet valves for said casing, arms connected to said inlet valves, rollers carried by said arms, springs connected to said arms and said casing, arms slidably connected to some of the spokes of said rotor, arms pivotally connected to other spokes of said rotor, said first named arms pivotally connected to said cams and said second named arms, weights carried by one of the ends of said arms, links pivotally connected to the other ends of said arms and to said cams, said cams adapted to engage said rollers for regulating the passage of steam through said inlet valves.

5. In a rotary engine, the combination of a casing, inlet valves carried by said casing, a rotor, auxiliary casings formed upon said casing, abutting plates slidably mounted in said auxiliary casings and adapted to move into or out of said casing, rods connected to said abutting plates, a plurality of levers connected to said rods, brackets formed upon said casing, pins carried by said brackets, arms connected to said pins, said arms having their free ends bifurcated, rollers seated in said bifurca-

tions and cams carried by said rotor, said cams adapted to engage said rotors and operate said arms for moving said abutment plates out of said casing and into said auxiliary casings, means for automatically moving said abutting plates into said casing after said rollers have passed over said cams, said rotor having a rim and spokes, arms connected to said inlet valves, rollers carried by said arms, springs connected to said arms and said casing and means carried by said rotor for engaging said rollers and operating said arms for controlling the passage of steam through said inlet valves.

6. In a rotary engine, the combination of a casing, inlet valves carried by said casing, a rotor, auxiliary casings formed upon said casing, abutting plates slidably mounted in said auxiliary casings and adapted to move into or out of said casing, rods connected to said abutting plates, a plurality of levers connected to said rods, brackets formed upon said casing, pins carried by said brackets, arms connected to said pins said arms having their free ends bifurcated, rollers seated in said bifurcations and cams carried by said rotor, said

cams adapted to engage said rotors and operate said arms for moving said abutment plates out of said casing and into said auxiliary casings, means for automatically moving said abutting plates into said casing after said rollers have passed over said cams, said rotor having a rim and spokes, arms connected to said inlet valves, rollers carried by said arms, springs connected to said arms and said casing, arms slidably connected to some of the spokes of said rotor, arms pivotally connected to other spokes of said rotor, said first named arms pivotally connected to said cams and said second named arms, weights carried by one of the ends of said arms, links pivotally connected to the other ends of said arms and to said cams, said cams adapted to engage said rollers for regulating the passage of steam through said inlet valves.

In testimony whereof I affix my signature in presence of two witnesses.

FRANK H. CARSON.
